UNITED STATES PATENT OFFICE.

HANS BUBECK, OF GRATZ, AUSTRIA-HUNGARY.

TABLE SIGNALING DEVICE.

1,034,685.

Specification of Letters Patent.

Patented Aug. 6, 1912.

Application filed December 1, 1911. Serial No. 663,420.

To all whom it may concern:

Be it known that I, HANS BUBECK, a citizen of the Republic of Switzerland, residing at Gratz, Styria, Austria-Hungary, have invented a certain Improved Table Signaling Device, of which the following is a specification.

The ordinary table bells used in restaurants and the like for calling the servants, have the disadvantage that they do not indicate with certainty at what table the call signal is given.

The object of the present invention is to remedy this defect and it is achieved by the combination with such a bell of a visible signal which remains in view after the bell has been rung, thereby indicating to the servants whence the call proceeded.

In the accompanying drawing the invention is illustrated by way of example, by a sectional view of the improved signaling device.

The device consists of a conical casing 1 which is supported on a base having a ring-shaped depression 2. This casing is surmounted by a head in which a recess is made to receive a brightly colored body 4 carried by a rod 5 and adapted to be pushed by means of the latter out of its recess. In the lower part of the casing 1, a double-armed lever 9 is mounted on a shaft 10 so as to protrude with one end out of the casing, the latter having a vertical slot in which the lever is guided. Another lever 12, mounted on a shaft 11, is guided in the same slot, the outer ends of both levers being connected by a link carrying a key 13 by means of which the levers may be depressed. A link 14 is also connected to both levers inside the casing 1 and is extended downward so as to actuate, by means of a spring 16, a double-armed lever 17 when the key 13 is depressed. The lever 17 has a ball 18 at one end and serves as clapper for a bell 21 connected to the bottom plate 3 of the casing 1. A press spring 20 holds the lever 17 normally against an abutment 19 and causes it to ring the bell when the end of the lever rids itself from contact with the spring 16 at the depression of the key 13.

Pivoted to the inner end of the lever 9 is a rod 8 which has its upper end guided in a longitudinal slot 6 in the rod 5. When

the lever 9 is turned by the depression of 55 the key 13, the rod 8 engages the rod 5 at the upper end of the slot 6 and raises the body 4 out of its recess. To retain the body 4 in raised position, while the other elements are restored to their normal position, a lug 7 is connected to the rod 5 so as to be engaged by the nose of a double-armed lever 22; the latter being held by a spring 23 against an abutment 24 with one end protruding out of the casing 1 so as 60 to allow of being depressed for releasing the body 4. A spring 26, connected to the shaft 10 and to the rod 8, tends to hold the levers 9 and 12, together with the elements connected thereto, in their normal position. 70 A padding 25 is arranged in the recess for the body 4 so as to prevent noise when the latter is dropped. From this arrangement it follows that when the key 13 is depressed for ringing the bell, the body 4 will be raised 75 into and retained in its visible position. Being brightly colored and thus easily perceived it will indicate to the servants where their services are wanted. The servant who answers the call also presses the lever 22 so 80 as to cause the body 4 to drop back into its recess.

The depression 2 may be employed for the reception of cigar ashes and burned matches.

The device may be complemented by a match holder and may be fitted with advertisements.

I claim:

In the herein described table signaling 90 device, the combination, with a conical casing having a recessed head, of audible signaling means arranged at the bottom of the casing and consisting of a bell and a clapper for ringing the same, a visible signaling 95 means, comprising a brightly colored body loosely fitted in the recess of said head, a slotted rod projecting from said body into the casing, a second rod the top end of which engages with the slot in the first rod, 100 a double armed lever connecting with its one end with the lower end of the second rod and projecting with its other end from the casing, a key carried by the projecting end of said double armed lever to allow of 105 depression of same, a second double armed lever connected to said key, a link connecting both levers, a spring secured to the

link which spring on the depression of the lever is adapted to operate the aforesaid clapper, and a third double armed spring influenced lever arranged at the upper part 5 of the casing and projecting with its lower arm therefrom, the upper arm providing the means for retaining the colored body | normally in position, all substantially as and for the purpose set forth and shown.

HANS BUBECK.
